United States Patent Office

Des. 229,987
Patented Jan. 15, 1974

229,987

PLAID TEXTILE FABRIC

Robert F. O'Brien, 1452 Glenlake Drive 46614, and Francis S. Amussen, 1657 N. Brookfield 46628, both of South Bend, Ind.

Filed Oct. 20, 1971, Ser. No. 191,150

Term of patent 14 years

Int. Cl. D5—05
U.S. Cl. D92—1 AA

Fig. 1

Fig. 2

FIG. 1 is a plan view of a textile fabric showing our new design; and

FIG. 2 is an enlarged fragmentary view of our new design lined for color and taken within line 2 of FIG. 1.

We claim:

The ornamental design for a plaid textile fabric, as shown and described.

References Cited

The Clans and Tartans of Scotland by Robert Bain, 1947, p. 295, Scott plaid shown.

House & Garden, March 1947, p. 63, item 31, plaid.

LOIS S. LANIER, Primary Examiner